UNITED STATES PATENT OFFICE.

SAMUEL SMITH, OF LAWRENCE, MASSACHUSETTS, ASSIGNOR OF ONE-HALF
TO WALTER A. LEIGH, OF CHELMSFORD, MASSACHUSETTS.

COMBING-MACHINE.

SPECIFICATION forming part of Letters Patent No. 579,187, dated March 23, 1897.

Application filed May 9, 1896. Serial No. 590,887. (No model.)

To all whom it may concern:

Be it known that I, SAMUEL SMITH, a citizen of the United States, residing at Lawrence, in the county of Essex and Commonwealth of Massachusetts, have invented a certain new and useful Improvement in Combing-Machines, of which the following is a specification.

My invention relates to combing-machines, such as are used in combing wool and similar fibers, in which machines the fibers are dabbed or beaten by quick blows of a brush onto teeth or pins arranged in two sets placed close together, which sets of teeth are then separated, a part of the fibers adhering to each set, the fibers from each comb or set of teeth being subsequently drawn through the teeth and united to form the combed "top," the shortest fibers or "noil" being retained by the combs. Such of the fibers as are not properly dabbed into the combs cannot be properly combed. Usually on starting the machine the combs begin to separate before the dabbing-brushes have attained their maximum speed and before the fibers are fully engaged with the teeth.

The object of this invention is to set the dabbing-brushes in operation before the combs begin to move and to stop the combs before the brushes are stopped.

In the accompanying drawings my invention is represented as applied to the well-known "Noble" comb, in which an outer revolving circular comb runs nearly tangentially to two smaller revolving inner circular combs, so that some of the teeth of the smaller combs are approaching and others are receding from the teeth of the larger comb at all times when the machine is in operation.

In the accompanying drawings, Figure 1 is a front elevation of such parts of a Noble comb provided with my invention as are necessary to the understanding of said invention, the combs being in vertical section; Fig. 2, an enlarged front elevation of the driving-pulleys, the main driving-shaft, from which the combs receive their motion, the dabber-driving shaft, pulley, and belts, and belt-shipping fork, the main driving-belt being in section; Fig. 3, a vertical section on the line 3 3 in Fig. 2 across the main shaft, dabber-

driving shaft, and belt-shipping fork, showing in side elevation the pulleys and belting.

The frame A, vertical hollow posts *a a*, supporting the main shaft B, the bevel-gears *b b* on said main shaft engaging other bevel-gears *c c* on the vertical shafts C C, spur-gears *c' c'* on said vertical shafts connected by the intermediate compound spur-gears D D to two other spur-gears *e e* on other vertical shafts E E, other spur-gears *e' e'*, fast on said shafts E E and engaging intermediate spur-gears *g g*, which in turn engage circular racks or gears *f f* on the smaller inner combs F F, and the larger comb H, having an internal annular gear or rack *h* engaged by the gears *f' f'*, are all of the usual construction and operation, the combs by the connecting shafts and gears above described being put in operation simultaneously with the main shaft. 70

Brackets *a' a'* on the posts *a a* support horizontal shafts I I, carrying band-pulleys *i i*, and eccentrics *i' i'* (indicated by dotted lines in Fig. 1) give motion to the eccentric strap or ring *i''* and to the eccentric-rod *i''*, pivoted to the shank *j* of the dabbing-brush J, and cause the dabbing-brush to have a vertical reciprocating movement at the points of contact of the large comb H with the smaller combs F F, all in the usual manner, except 80 that the shafts I I are usually driven by belts directly from the main shaft, while I drive said shafts I I from a counter-shaft K by belt L, connecting the pulleys *i i* and other pulleys *k k*, fast on said counter-shaft. The counter-shaft K is supported above said main shaft and turns in suitable stands *a'' a''*, preferably cast on or otherwise secured to the usual enlarged heads *a'' a''* of the hollow posts *a a*. 85

The main shaft B is provided with a fast 90 pulley *b'* and with a loose pulley *b''* in the usual manner, except that the face of said loose pulley *b''* is herein shown much wider than that of the fast pulley *b'* instead of being of the same width, and the counter-shaft 95 K is also provided with a fast pulley *k'* and with a loose pulley *k''*, the face of the pulley *k'* being much wider than the face of the loose pulley *k''*, the combined width of the pulleys *k' k''* equaling that of the pulleys *b' b''*. The 100 pulleys *k' k''* of the counter-shaft are driven by a belt *k''* from the pulleys *b' b''* of the main

- shaft B, and said pulleys $b' b^2$ are driven by a main driving-belt M, which rides or runs on the belt k^3 , Fig. 3, and both these belts M k^3 are together shifted by the belt-shifting bar 5 N, provided with a belt-fork n, which receives both belts, just as the main driving-belt is commonly shifted, said shipping-bar sliding in the usual manner in straps $a^4 a^4$, secured on the hollow posts a a.
- 10 It is evident that when the running belts M k^3 are together shifted from the loose pulleys $b^2 k^2$ to the fast pulleys $b' k'$ the belt k^3 will run onto the fast pulley k' of the counter-shaft K and set said counter-shaft and 15 the dabbing-brushes in motion before running onto the fast pulley b' of the main shaft B and setting the combs in motion; also, that when these belts are shifted in the opposite direction said belts will leave the fast pulley b' on the main shaft before leaving the fast pulley k' of the counter-shaft, so that the dabbing-brushes will continue to move at 20 full speed after the combs nearly or quite stop.
- 25 I claim as my invention—
1. The combination of the combs and dabbing-brushes of a combing-machine, a main shaft and intermediate mechanism for driving said combs, a counter-shaft and mechanism connecting the same and the main shaft for driving said brushes and comprising a 25 fast pulley and a loose pulley on each of said shafts, the combined width of the fast pulley

and loose pulley on each shaft being equal to that of the fast pulley and loose pulley on the 35 other shaft and the fast pulley on the counter-shaft being wider than the fast pulley on the main shaft, a belt connecting the pulleys of said shafts, and a main driving-belt running on said first-named belt, as and for the 40 purpose specified.

2. The combination of the combs and dabbing-brushes of a combing-machine, a main shaft and intermediate mechanism for driving said combs, a counter-shaft and mechanism 45 connecting the same and the main shaft for driving said brushes and comprising a fast pulley and a loose pulley on each of said shafts, the combined width of the fast pulley and loose pulley on each shaft being equal to 50 that of the fast pulley and loose pulley on the other shaft and the fast pulley on the counter-shaft being wider than the fast pulley on the main shaft, a belt connecting the pulleys of 55 said shafts, a main driving-belt running on said first-named belt, and shifting mechanism for simultaneously shifting said belts, as and for the purpose specified.

In witness whereof I have signed this specification, in the presence of two attesting witnesses, this 4th day of May, A. D. 1896.

SAMUEL SMITH.
